VOLTAGE REGULATOR CIRCUIT

William L. Kinsell, Fort Wayne, Ind., assignor, by
mesne assignments, to Farnsworth Research
Corporation, a corporation of Indiana

Application June 14, 1947, Serial No. 754,757

6 Claims. (CL. 323—41)

1

This invention relates to regulated power supplies and particularly to a voltage regulator circuit wherein the output voltage rises slowly to the predetermined value to prevent damage of the load fed by the regulator.

A conventional voltage regulator comprises a rheostat tube connected in series with a direct current supply and the load. The rheostat tube is controlled by a high gain amplifier responsive to variations of the output voltage. The regulator action accordingly depends on the control tube which varies the grid bias of the rheostat tube and hence the current flowing through the load. The direct current supply conventionally consists of a full wave rectifier and a filter network which supply the unregulated power. When the full wave rectifier circuit is turned on, it will heat up almost instantaneously and supply the full power to the rheostat tube. The rheostat tube in turn may be a directly heated tube which will also heat up practically instantaneously. Alternatively, the recently developed 6AS7 tube may be used for the rheostat tube which, although indirectly heated, will also be operative in a comparatively short time. On the other hand, the control tube is a high gain amplifier such as a pentode which will require an interval of time of the order of ten seconds before it becomes effective to control the rheostat tube.

Consequently, when the power is turned on, the output voltage developed by a conventional voltage regulator will initially be considerably higher than the desired value which may damage the load. The load of a voltage regulator frequently consists of amplifier tubes which are easily damaged when too high a voltage is applied thereto. It is accordingly desirable to provide a voltage regulator having an output voltage which rises slowly until the control tube becomes effective for controlling the current through the rheostat tube.

It is an object of the present invention, therefore, to provide an improved voltage regulator circuit.

A further object of the invention is to provide a voltage regulator of the type having a rheostat tube controlled by a high gain amplifier tube responsive to variations of the output voltage, with a time delay circuit to prevent a too rapid rise of the output voltage when the regulator

2

is turned on which might damage the load fed by the regulator.

In accordance with the present invention there is provided a voltage regulator comprising a direct current supply, a load and a rheostat tube for regulating the voltage of the supply and connected in series with the direct current supply and the load. The rheostat tube has a control element. There is further provided a control tube responsive to variations of the voltage across the load. The control tube has an output electrode. The output electrode of the control tube is connected to the control element of the rheostat tube. Furthermore, there is provided a time delay circuit. Finally means is provided for coupling the time delay circuit to the control element of the rheostat tube. The time delay circuit accordingly functions to delay the current flow through the rheostat tube until the control tube becomes effective to control the voltage across the load.

For a better understanding of the invention, together with other and further objects thereof, reference is made to the following description, taken in connection with the accompanying drawing, and its scope will be pointed out in the appended claims.

The single figure of the drawing is a schematic circuit diagram of a voltage regulator embodying the present invention.

Referring now to the drawing, there is shown a voltage regulator comprising a direct current source such as a full wave rectifier circuit. Transformer 1 has a primary winding 2 which is connected to an alternating current source as indicated through a switch 3. Full wave rectifier tube 4 has its anodes connected to secondary winding 5, the mid point of which is connected to ground through lead 15. The cathode of full wave rectifier tube 4 is directly heated by secondary winding 6 and is connected to a filter network indicated at 7. Filter network 7 includes two series choke coils 8 and 10 having their terminals by-passed to ground by shunt condensers 11, 12 and 13. The unregulated voltage is obtained between positive output lead 14 and negative output lead 15 connected to ground.

Rheostat tube 16 may consist of two tube sections connected in parallel as illustrated. Rheo-

stat tube 16 is provided in positive output lead 14 and thus is connected in series with the full wave rectifier circuit and a load schematically indicated at 17. Rheostat tube 16 has its anodes connected to filter network 7 while its cathodes are connected to load 17. The two control grids 18 of rheostat tube 16 are connected together and control the current flow through tube 16.

Rheostat tube 16 is controlled by a control tube 20 which, as illustrated, may be a pentode or any other high gain amplifier tube. Control tube 20 comprises cathode 21, control grid 22, screen grid 23, suppressor grid 24 and anode 25. Anode 25 is connected to control grids 18 of rheostat tube 16. For the purpose of controlling control tube 20 in accordance with the variations of the voltage across load 17 there is provided a potentiometer including resistors 26, 27 and 28 connected in series across load 17. Control grid 22 is connected by lead 29 to adjustable tap 30 on resistor 27. Condenser 31 shunts leads 14 and 29, that is resistor 26 and that portion of resistor 27 arranged between resistor 26 and adjustable tap 30.

Control tube 20 is also made responsive to the voltage variations across filter network 7. To this end there is provided another voltage divider including resistors 32 and 33 and voltage regulator tubes 34 and 35 connected in series across leads 14, 15. Voltage regulator tubes 34, 35 may be gas-filled diodes such as glow discharge tubes having a constant voltage drop thereacross. Screen grid 23 of control tube 20 is connected to adjustable tap 36 on resistor 33.

Cathode 21 of control tube 20 is connected to the junction point of voltage regulator tubes 34 and 35, while suppressor grid 24 is tied to cathode 21. Cathode 21 of control tube 20 may be indirectly heated by a filament 37 connected to secondary winding 38 of transformer 1 having one of its terminals grounded. The cathodes of rheostat tube 16 may also be indirectly heated through secondary winding 40 of transformer 1 which has its center point grounded as illustrated.

In accordance with the present invention there is provided a time delay network consisting of the series combination of resistor 41 and condenser 42 connected across load 17, that is, in parallel to voltage divider 26, 27 and 28. Resistor 43 connects the junction point of resistor 41 and condenser 42 to the junction point of anode 25 of control tube 20 and control grid 18 of rheostat tube 16.

The voltage regulator of the invention operates as follows. The full wave rectifier circuit including rectifier tube 4 develops a unidirectional current which is filtered by filter network 7. The amount of current flowing through rheostat tube 16 and accordingly through load 17 is determined by the bias of its control grids 18. This bias is controlled, as is conventional, by the current flowing through control tube 20. Assume, for example, that the voltage across load 17 is reduced below the desired value due either to an increase of the current through load 17 or due to a decrease of the voltage impressed upon the primary winding 2. Accordingly, the voltage on adjustable tap 30 will be reduced so that less current flows through control tube 20. Consequently, the voltage drop across resistors 41 and 43 is reduced which increases the bias of control grids 18 and permits more current to flow through rheostat tube 16.

In the same manner control tube 20 is also responsive to variations of the voltage derived

across filter network 7. Assume that the output voltage of the full wave rectifier circuit is reduced. The voltage drop across resistors 32 and 33 is accordingly reduced which will in turn reduce the potential of screen grid 23. This will have the same effect as previously described so that the current through rheostat tube 16 is increased, and consequently, the output voltage remains constant.

By adjusting tap 36, the regulator action of the circuit may be adjusted to zero or may even be made negative. Voltage regulator tube 34 serves the purpose of impressing a constant voltage between screen grid 23 and cathode 21 of control tube 20 to which is added a variable voltage which may then be adjusted by movable tap 36 to obtain the desired regulation action.

As pointed out hereinbefore, full wave rectifier tube 4 and rheostat tube 16 will become operative almost instantaneously while control tube 20, which is a pentode, requires more time before it becomes effective for controlling the current through rheostat tube 16. Accordingly, immediately after switch 3 has been closed to supply power to the voltage regulator, a fairly high output voltage would ordinarily be developed across load 17. In order to provide for a slow rise of the output voltage, the time delay circuit consisting of resistor 41 and condenser 42 is provided in the circuit of control grids 18 of rheostat tube 16. The time constant of resistor 41 and condenser 42 may, for example, be of the order of two seconds.

As long as no power is applied to the voltage regulator, condenser 42 will be discharged and control grids 18 will accordingly be at ground potential. When switch 3 is closed, the full voltage developed by the rectifier circuit is applied to the anodes of rheostat tube 16. Since its control grids 18 are initially at ground potential, only a small current can flow through rheostat tube 16 which will slightly increase the potential of condenser 42. In view of the de-generative action of the time delay circuit 41, 42, it will require approximately between 15 and 20 seconds before the potential of control grids 18 is raised to its normal operating value. During that time, control tube 20 has become fully operative for controlling the current through rheostat tube 16 in the manner previously described. The voltage regulator of the present invention accordingly provides a simple and effective circuit which will prevent damage of the load when the voltage regulator is turned on.

The output voltage supplied to load 17 may be adjusted by tap 30. Adjustment of tap 30 will change the voltage between cathode 21 and control grid 22 of control tube 20 which must be kept within very narrow limits. Accordingly, control tube 20 will regulate the current through rheostat tube 16 until the potential between cathode 21 and control grid 22 is again at the value required for the operation of the tube, and consequently this will adjust the output voltage within certain limits.

While it will be understood that the circuit specifications of the voltage regulator of the invention may vary according to the design for any particular application, the following circuit specifications for a voltage regulator are included, by way of example only, as suitable for an output voltage variable between 200 and 350 volts and a maximum continuous output current of 100 milli-amperes with a 60 cycle alternating

input voltage which may vary between 90 and 130 volts:

Full wave rectifier tube 4	5U4
Rheostat tube 18	6AS7
Control tube 20	6SJ7
Voltage regulator tube 34	VR75
Voltage regulator tube 35	VR75
Output voltage of secondary heater winding 38	6.3 volts
Output voltage of secondary heater winding 40	6.3 volts
Choke coil 8	150 milli-henries
Choke coil 10	150 milli-henries
Filter condenser 11	4 microfarads
Filter condenser 12	4 microfarads
Filter condenser 13	4 microfarads
Resistor 32	15,000 ohms
Resistor 33	10,000 ohms
Resistor 41	1,000,000 ohms
Condenser 42	2 microfarads
Resistor 43	560,000 ohms
Condenser 31	.1 microfarad
Resistor 26	47,000 ohms
Resistor 27	100,000 ohms
Resistor 28	27,000 ohms

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A voltage regulator comprising a direct current supply, a load, a rheostat tube for regulating the voltage of said supply and connected in series with said supply and said load, said rheostat tube having a control element, a control tube responsive to variations of the voltage across said load and having a cathode, an anode and a control grid, a voltage divider connected across said load, said control grid and cathode being coupled to said voltage divider, said anode being connected to said control element, a time delay circuit coupled to the output of said rheostat tube and including a first impedance element and a charge storage element, and means for coupling the junction point of said first impedance element and said charge storage element to said control element, thereby to delay the current flow through said rheostat tube until said control tube becomes effective to control the voltage across said load.

2. A voltage regulator comprising a direct current supply, a load, a rheostat tube for regulating the voltage of said supply and connected in series with said supply and said load, said rheostat tube having a control element, a control tube responsive to variations of the voltage across said load and having a cathode, an anode and a control grid, a voltage divider connected across said load, said control grid being connected to a tap on said voltage divider, means coupled to said supply for maintaining said cathode at a predetermined potential, said anode being connected to said control element, a time delay circuit connected in parallel to said voltage divider and including a first impedance element and a condenser, and a second impedance element connected between the junction points of said first impedance element and condenser and of said anode and control element, thereby to delay the

current flow through said rheostat tube until said control tube becomes effective to control the voltage across said load.

3. A voltage regulator comprising a direct current supply, a load, a rheostat tube for regulating the voltage of said supply and connected in series with said supply and said load, said rheostat tube having a control element, a high gain control tube responsive to variations of the voltage across said load and having a cathode, an anode and a control grid, a voltage divider connected across said load, said control grid being connected to an adjustable tap on said voltage divider, a constant voltage drop diode coupled to said supply for maintaining said cathode at a predetermined potential, said anode being connected to said control element, a time delay circuit having a predetermined time constant and by-passing said load, said circuit including a first resistor and a condenser connected in series, and a second resistor connected between the junction points of said first resistor and condenser and of said anode and control element, thereby to delay the current flow through said rheostat tube until said control tube becomes effective to control the voltage across said load.

4. A voltage regulator comprising a direct current supply, a load, a rheostat tube having a control element and connected in series with said supply and said load for regulating the voltage of said supply, a first voltage divider connected across said load, a second voltage divider connected across said supply, a control tube having a cathode, an anode, a control grid and a screen grid, said anode being connected to said control element, said control grid being connected to a tap on said first voltage divider, said screen grid being connected to a tap on said second voltage divider, means coupled to said supply for maintaining said cathode at a predetermined voltage, whereby said control tube is responsive to voltage variations across said supply and across said load, an impedance element and a condenser connected in series across said load and having a predetermined time constant, a resistor connected between the junction points of said impedance element and condenser and of said anode and control element, thereby to delay the current flow through said rheostat tube until said control tube becomes fully effective to control said rheostat tube.

5. A voltage regulator comprising a direct current supply, a load, a rheostat tube having a control element and connected in series with said supply and said load for regulating the voltage of said supply, a first voltage divider connected across said load, a second voltage divider and a constant voltage drop tube connected across said supply, a control tube having a cathode, an anode, a control grid and a screen grid, said anode being connected to said control element, said control grid being connected to a tap on said first voltage divider, said screen grid being connected to a tap on said second voltage divider, said cathode being connected to the junction point of said second voltage divider and said constant voltage drop tube, whereby said control tube is responsive to voltage variations across said supply and across said load, a first resistor and condenser connected in series across said load and having a predetermined time constant, a second resistor connected between the junction points of said first resistor and condenser and of said anode and control element, thereby to delay the current flow through said rheostat tube

until said control tube becomes fully effective to control said rheostat tube.

6. A voltage regulator comprising a direct current supply, a load, a rheostat tube having a control element and connected in series with said supply and said load for regulating the voltage of said supply, a first voltage divider connected across said load, a second voltage divider and a first and a second constant voltage drop diode connected across said supply, a high gain control tube having a cathode, an anode, a control grid and a screen grid, said anode being connected to said control element, said control grid being connected to an adjustable tap on said first voltage divider, said screen grid being connected to an adjustable tap on said second voltage divider, said cathode being connected to the junction point of said diodes, whereby said control tube is responsive to voltage variations across said supply and across said load, a first resistor and condenser connected in series across said load and

having a predetermined time constant, a second resistor connected between the junction points of said first resistor and condenser and of said anode and control element, thereby to delay the current flow through said rheostat tube until said control tube becomes fully effective to control said rheostat tube.
